UNITED STATES PATENT OFFICE.

CLIFFORD A. FLOWERS, OF CAMDEN, OHIO.

REPAIR-SHOE FOR CORN-PLANTERS.

1,178,146.

Specification of Letters Patent.

Patented Apr. 4, 1916.

Application filed May 22, 1914. Serial No. 840,306.

To all whom it may concern:

Be it known that I, CLIFFORD A. FLOWERS, a citizen of the United States, residing at Camden, in the county of Preble and State 5 of Ohio, have invented certain new and useful Improvements in Repair-Shoes for Corn-Planters, of which the following is a specification.

This invention relates to certain new and 10 useful improvements in quick repair shoes for corn planters, and is designed as an improvement over a similar device subsequently invented by me and patented February 20, 1912, bearing Patent #1018105.

15 The primary object of the invention is to provide a simple and inexpensive repair shoe or sole adapted to fit all standard makes of planter shoes for replacing and renewing the original worn out shoe.

20 A further object of the invention contemplates the provision of a three piece repair shoe, wherein the center piece is constructed in such a novel and peculiar manner as to space the sides sufficiently to permit a perfect 25 fit of the device to the original shoe, also presenting a solid metallic center to the ground for increasing the wearing surface and materially adding to the longevity of the device.

30 A still further object of the invention resides in the provision of locking means including a single slot formed within each side piece or section of the shoe, through which a single transverse bolt extends, thereby allowing 35 adjustment of the shoe, the said slots being disposed upon an angle to prevent upward movement of the bolt when adjusted or tightened.

The above and additional objects are 40 accomplished by such means as are illustrated in their preferred embodiment in the accompanying drawings, described in the following specification, and then more particularly pointed out in the claim which is appended hereto and forms a part of this application.

In describing my invention in detail reference will be had to the accompanying drawings, wherein like characters denote like 50 or corresponding parts throughout the several views, and in which:

Figure 1 is a side elevation of a repair shoe constructed in accordance with my invention, illustrating the application thereof; Fig. 2 is a rear end view, the planter

shoe being shown in section; and Fig. 3 is a detail perspective view of the repair shoe.

Referring now more particularly to the drawings, wherein is illustrated the preferred form of my invention, the numeral 60 1 designates a corn planter runner or furrow opener of any of the well known forms of construction, to which the repair shoe comprising my invention is secured. The said shoe, designated in its entirety by the numeral 65 2, is preferably composed of three pieces or sections, a center piece 3, and two side pieces or sections 4 and 5 which are welded or otherwise secured, as is clearly shown at 6 in Fig. 3 of the drawings to the said center piece 3. 70 The lower extremity of the sections 4 and 5 are tapered as at 7 to present a smooth outer surface to the shoe when properly assembled, the said sections 4 and 5 being held parallel and in spaced relation by means of 75 the section 3 which is fitted therebetween. By the provision of the space or passageway, above mentioned, it will be seen that the repair shoe may be quickly fitted upon the runner 1 of the planter and secured thereto 80 in a manner to be hereinafter fully described. The forward extremity of the shoe 2 is cut upon an angle as is shown in Fig. 1 of the drawings, and made to present a solid metallic surface to the ground during the 85 operation of the device, thus materially prolonging the life and usefulness of the shoe. The opposite or rear end of the said shoe is made upon an angle opposite to that of the forward end, this construction allowing the 90 shoe to be set back the required distance to prevent dirt from falling in the corn furrow during operation. The plates or shoe sections being welded or otherwise secured as at 95 6, and the lower edge 8 of the central section 3 conforming approximately to the contour or configuration of the lower edge of the planter shoe 1, it will be seen that the corn furrow is cut and kept clear of falling dirt 100 as desired.

Having described fully the detail construction of the shoe proper, the manner in which the same is secured or locked to the casing 1 of the planter will now be described.

A pair of parallel angularly disposed slots 9 are arranged oppositely, one within each of the side sections 4 and 5 of the shoe, the said slots extending in a plane substantially parallel with that of the rear face or 110

edge of the shoe. By this arrangement, the desired adjustment of said shoe upon the runner is permitted, after which a secure locking or fastening of the said shoe in such 5 adjusted position is accomplished through the medium of a transversely extending bolt 10 fitting within the said slots and extending transversely through the said shoe, where it is held against movement in any 10 direction by means of a nut 11 threaded thereupon.

It will be seen from the above, taken in connection with the accompanying drawings, that the provision of a three piece shoe 15 will decrease the cost of manufacture and at the same time create a device susceptible of application to any of the standard planter shoes now in use; that the provision of a single pair of oppositely disposed angular slots 20 will allow adjustment of the shoe to various positions and angles that are necessary in practical application; and that the simplicity of the device itself, as well as the manner in which it is fastened or locked upon 25 the runner will greatly add to the efficiency and desirability of the device.

While the description herein given has been directed particularly to planter shoes, it is obvious that the sole or repair shoe comprising the invention may also be advan- 30

tageously applied to listers or similar implements.

It will be understood that the above description and the accompanying drawings comprehend only the general and preferred embodiment of my invention, and that various minor changes in details of construction, proportion, and arrangement of parts may be made within the scope of the appended claim, and without sacrificing any 40 of the advantages of the invention.

Having thus fully described my invention, what I claim as new and desire to secure by Letters Patent, is:—

A repair shoe for corn planters comprising side sections made of an inferior material, a central section made of a higher grade of material, each of the side sections being provided with a single angularly disposed slot, said slots being alined, and a single fastening element fitting the alined slots to contact with the planter and to permit of both vertical and angular adjustment relatively thereto, substantially as described.

In testimony whereof I affix my signature in presence of two witnesses.

CLIFFORD A. FLOWERS.
